UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

SPOOLER FOR WINDING SPOOLS OF DIFFERENT LENGTHS.

Application filed November 1, 1924. Serial No. 747,144.

To all whom it may concern:

Be it known that I, ALONZO E. RHOADES, a citizen of the United States, and a resident of Hopedale, county of Worcester, 5 State of Massachusetts, have invented an Improvement in Spoolers for Winding Spools of Different Lengths, of which the following description, in connection with the accompanying drawing, is a specification, 10 like characters on the drawing representing like parts.

This invention relates to improvements in spoolers and the general object of the invention is to provide a spooler adaptable to 15 wind spools of different lengths simultaneously.

Usual spool carriers comprise a frame having a series or a plurality of series of spool carriers with means for rotating said 20 spool carriers uniformly and a traverse rod having guides co-operating with the respective spools of a series. Such spoolers are capable of winding only spools of the same uniform length and when spools of other 25 lengths are to be wound it is necessary to reorganize the entire spooler in order to wind properly the spools of the desired length. Where small orders are received for spools which are of different lengths from 30 the spools for which the machine is adapted such reorganization of the spooler is very burdensome.

The principal object of the present invention therefore is to provide a spooler which may be of any desired size and which is so constructed that one or more sections of it may be readily adapted to wind spools of different lengths than those of the other section or sections without interfering with 40 the winding of the regular spools upon such other section or sections.

A further object of the invention is to provide a spooler having a series of rotatable spool carriers and means for imparting uniform rotation to all of said spool carriers with a plurality of traverse rods each operated by a separate and independent traverse mechanism comprising changeable, preferably replaceable, means for correlating the movement of the traverse rod to the speed of rotation of the spool and the length of the spool in order that spools of different lengths may be properly wound simultaneously upon the spooler.

55 A further object of the invention is to

provide a device of this character with a common means for actuating all of the traverse mechanisms.

A further object of the invention is to provide a traverse motion shaft for actuating the several traverse mechanisms with means for preventing breakage of the traverse motion mechanisms if the same are 60 improperly arrested.

Other objects and features of the invention will more fully appear from the following description and the accompanying drawings and will be particularly pointed out in the claims.

In the drawings:

Fig. 1 is a side elevation of a preferred form of spooler embodying the invention showing a plurality of independently operated traverse rods for winding spools of different lengths;

Fig. 2 is a sectional view through the spooler frame viewed toward the driving end and illustrating a preferred form of traverse mechanism;

Fig. 3 is a detail side elevation of a portion of the spooler embodying the invention showing the particular and preferred form of traverse mechanism and means for actuating the same.

The spooler as illustrated in the accompanying drawings comprises a frame which is shown as formed in sections, each section comprising a plurality of supporting uprights or samsons 1 connected by longitudinally extending beams 2 and connecting rods 3 which desirably extend throughout the series of the sections of the frame. The longitudinal members of the frame are connected by suitable cross struts 4 which preferably are formed integral with the uprights. All of these members may be of any suitable and desired form. Horizontal spindle rails 5 are formed upon or secured to the upper edges of the longitudinal beams 4 and a series of rotatable spindles 6 is mounted upon each of the spindle rails. Each spindle is provided with a whirl 7 which is driven by a suitable belt (not shown) from a drum 8 which is mounted upon the main shaft 9 which extends longitudinally of the frame and is actuated in any suitable manner as through fast and loose pulleys 10 and 11.

The spools are mounted upon the spindles and the yarn is supplied to each spool from

a yarn carrier or bobbin which is mounted in a suitable holder positioned opposite the spool. The spool holder may be of any suitable form and one familiar form is illustrated herein as comprising a bracket 12 secured to rods 13 which extend longitudinally of the machine in front of the beams 4 and is provided with a bed or seat 14 upon which the bobbin rests and a tension or control device 15. The yarns extend from the respective bobbins to the corresponding spools and run through suitable guides 16 mounted upon the traverse rods which extend longitudinally of the machine in front of the spools. In usual machines these traverse rods extend throughout the entire length of the machine in parallelism with the side beams 2 and are reciprocated vertically by the traverse mechanism so that the machine is adapted only to wind spools of the same length.

In the present invention a plurality of traverse rods are provided upon each side of the machine. In the present illustration three of such traverse rods 17, 18 and 19 are illustrated, such rods preferably being in axial alignment and similarly located on both sides of the machine.

Each traverse rod, or preferably each pair of traverse rods, is actuated by a separate and independent traverse mechanism and desirably all of the traverse mechanisms are actuated from a single traverse motion shaft which extends throughout the entire length of the machine. The traverse mechanism for reciprocating each of the traverse rods may be identical with or similar to that for actuating the other traverse rods and each traverse mechanism may be provided with means for varying the amplitude of traverse and the speed of traverse adapted to wind spools of different length. A description therefore of one of the traverse and lifting mechanisms will serve as a description for all.

The lifting mechanism illustrated herein comprises a plurality of yoke-shaped members 20 the upper horizontal ends of which are pivoted in brackets or uprights 21 mounted on the spindle rails and located at intervals along the rails preferably in proximity to the ends of the respective traverse rods. Upon each of the horizontal ends of said yoke a lifter arm 22 is pivotally mounted which is pivotally connected at its free end to a link 23 which is secured to the traverse rod. Each of the yokes is provided with an extension 24 which lies beneath and preferably partially embraces the arm 22 so that as the yoke-shaped members 20 are swung in a clockwise direction about their pivots the traverse rod with its guides will be raised thus directing the yarn which passes through the guide upwardly in parallelism with the axis of the

spool. Upon oscillation of the yoke-shaped members in a reverse direction by the action of gravity or otherwise the traverse rod will be correspondingly lowered thus providing for the traverse of the yarn upon the spool.

Any suitable mechanism which is adaptable or changeable to produce different lengths of traverse of the traverse rod and such different rates of movement thereof as will correlate the movement of the traverse rod to the speed of rotation of the spool and the length of the spool may be employed.

In the preferred embodiment of the invention illustrated the yokes 20 for each traverse rod are connected together by rods 25 and one of each set of yokes is connected by a link 26 to the upper end of an arm 27 of a bell crank lever which is fulcrumed upon a stud 28 in the end of a bracket 29 carried by an upright 1. The other arm 30 of the bell crank lever is connected by a link 31 to the offset end 32 of a lever 33 which is pivotally mounted upon a stud 34 carried by the arm 35 of a bracket 36 which is secured to the upright 1. The lever 33 is provided adjacent the shoulder of the offset portion with a cam-following roll 37 which engages the periphery of a suitable, preferably heart-shaped cam 38 which is rotatably mounted upon a stud shaft 39 projecting from an upwardly extending arm 40 of the bracket 36. A gear 41, which is also rotatably mounted upon the stud shaft 39, desirably is secured to the cam by pins 42, or the gear and cam may be made integral and both desirably are detachably secured upon the stud shaft as by a pin 43 extending through a suitable aperture in the shaft. By reason of this construction the cam and its gear can be readily removed and replaced to provide for the proper actuation of the traverse rod for spools of different lengths.

Any suitable means may be employed for rotating the cam and its gear. In the preferred embodiment of the invention illustrated a single traverse motion shaft 44 extends longitudinally of the machine and is provided with gears 45 to co-operate with the gears of the several cams which operate the respective traverse rods as above described.

Inasmuch as gears of different diameters are required for the different cams properly to correlate the speed of movement of the traverse rod to the length of spool and its rotation adjustable means are provided for transmitting the rotation to the cam gear from the gear upon the traverse motion shaft. This is conveniently accomplished in the present invention by adjustably mounting the shaft 46 of an idle gear 47 in a slot 48 in an arm 49 extending laterally from the upper portion of the member 40 of the

bracket 36 so that the shaft of the idle gear may be properly secured to the bracket to cause the teeth of the gear to mesh with the teeth of the gear 45 upon the traverse motion shaft and also with the gear 41 which is secured to the cam.

In Fig. 2 the gear 47 is shown in full lines as meshing with the gear 45 and in dotted lines as meshing with the gear 41. There is also illustrated in dotted lines two other heart-shaped cams of smaller diameter which may be substituted together with their suitable gears for the cam 38 and its gear 41 to provide for the proper actuation 15 of the traverse rod to wind spools of shorter lengths.

Any suitable means may be provided for actuating the traverse motion shaft 44. As illustrated herein the shaft 44 has secured 20 to it a worm gear 50 which is rotated by a worm 51 mounted upon a shaft 52 which is journalled in a bracket 53 secured to the upright 1. A bevelled gear 54 is formed integral with or secured to the worm gear 51 and is engaged by a complementary bevelled gear 55 which is rotatably mounted upon a countershaft 56 which is driven by a sprocket wheel 57 and sprocket chain 58 from a sprocket wheel 59 upon the main 30 shaft 9.

By reason of the construction thus described the traverse motion shaft 44 is given a positive rotation and cannot slip or yield to any stoppage of the traverse mechanism.

35 A further feature of the invention consists in providing means which will permit the slippage of the driving mechanism of the respective traverse motions to prevent breakage of the traverse mechanism or other parts. This is accomplished in the present invention by rotatably mounting the gear 45 upon the traverse motion shaft 44 and providing a suitable clutch mechanism which will normally cause rotation of the gear with the shaft, but which upon arrest of the traverse mechanism will permit a slippage of the gear upon the shaft.

40 In the particular embodiment of the invention disclosed herein the hub of the gear 45 is provided with a circular series of V-shaped teeth adapted to engage complementary teeth upon a collar 60 which is secured to the traverse motion shaft. The teeth of the gear hub and collar are normally held in engagement by a heavy helical spring 61 which surrounds the shaft 44 and abuts at one end against the hub of the gear 45 and at its opposite end against a collar 62 which is fixedly secured to the shaft as by 45 a pin 63.

45 In the operation of the machine above described each of the traverse rods is reciprocated by its separate traverse mechanism, all of the traverse mechanisms being actuated 50 from the traverse motion shaft which ex-

tends throughout the length of the machine. When it is desired to wind spools of equal length identical cams and cam gears are applied to the stud shafts 46 carried by the respective uprights which desirably are located at the ends of the sections of the frame containing the respective groups of spindles with which the several traverse rods co-operate. When it is desired to wind a 70 relatively small number of spools of different lengths than those for which the machine is thus equipped one or more of the cams and attached cam gears can be readily removed from its stud shaft and replaced by a different cam with its attached gear which will correlate the reciprocating movement of the traverse rod to the speed of rotation of the spools and the length of the spools with which such traverse rod co-operates.

75 By reason of this construction therefore one or more groups of the series of rotatable spool carriers may be utilized to wind spools of a different length than the other spools of the series. Furthermore by reason of this construction the entire machine can be readily adapted to wind spools of any desired 80 length by merely using such cams and their attached gears as are required to impart the proper motion to the traverse rods.

85 It will be understood that the embodiment of the invention disclosed herein is of an 90 illustrative character and is not restrictive and that various changes in form, construction and arrangement of parts may be made within the spirit and scope of the following 95 claims.

Having thus described the invention, what is claimed as new, and desired to be secured by Letters Patent, is:

1. A spooler adaptable to wind spools of different lengths simultaneously comprising a series of rotatable spool carriers and means for rotating the same, a plurality of separately movable traverse rods having guides, each of which co-operates with a spool of 100 said series, means for actuating each of said 105 traverse rods independently of the others in correlation to the speed of rotation of the spools and the length of the spools with 110 which such traverse rod co-operates.

115 2. A spooler adaptable to wind spools of different lengths simultaneously comprising a series of rotatable spool carriers and means for rotating the same, a plurality of separately movable traverse rods having guides, each of which co-operates with a spool of 120 said series, means for actuating each of said 125 traverse rods independently of the others comprising changeable means for correlating the movement of the traverse rod to the speed of rotation of the spools and the length of the spools with which such traverse rod co-operates.

3. A spooler adaptable to wind spools of 130 different lengths simultaneously comprising

3 a series of spool carriers, means for imparting uniform rotation to all of said spool carriers, a plurality of traverse rods having guides co-operating with the respective 65
 5 spools of a group of said series of spools, a traverse motion shaft, separate traverse mechanisms actuated by said traverse motion shaft and connected to the respective traverse rods operable to reciprocate said re- 70
 10 spective traverse rods in correlation to the speed of rotation of the spools and the length of the spools with which the respective traverse rods co-operate.

15 4. A spooler adaptable to wind spools of different lengths simultaneously comprising a series of spool carriers, means for imparting uniform rotation to all of said spool carriers, a plurality of traverse rods having guides co-operating with the respective 80
 20 spools of a group of said series of spools, a traverse motion shaft, separate traverse mechanisms actuated by said traverse motion shaft and connected to the respective traverse rods comprising replaceable means 85
 25 operable selectively to reciprocate the respective traverse rods in correlation to the speed of rotation of the spools and the length of the spools with which the respective traverse rods co-operate.

30 5. A spooler adaptable to wind spools of different lengths simultaneously comprising a series of rotatable spool carriers, means for imparting uniform rotation to all of said spool carriers, a plurality of traverse rods having guides co-operating with the respective 90
 35 spools of a group of spools of said series, a traverse motion shaft, separate traverse mechanisms actuated by said traverse motion shaft connected to the respective 95
 40 traverse rods and comprising replaceable cams and gears operable to reciprocate the respective traverse rods in correlation to the speed of rotation of the spools and the length of the spools with which such traverse rods co-operate.

45 6. A spooler adaptable to wind spools of different lengths simultaneously comprising a series of rotatable spool carriers, means for imparting uniform rotation to all of said spool carriers, a plurality of traverse rods having guides co-operating with the respective 100
 50 spools of a group of spools of said series, a traverse motion shaft, separate traverse mechanisms actuated from said traverse motion shaft and connected to the respective 105
 55 traverse rods, each traverse mechanism comprising a cam shaft, a cam having a gear rotatably and detachably mounted upon said cam shaft and an idle pinion adjustably
 60 mounted to engage the cam gear and a complementary gear upon said traverse motion shaft.

7. A spooler for winding spools of different lengths simultaneously comprising a series of rotatable spool carriers, means for imparting uniform rotation to all of said spool carriers, a plurality of traverse rods having guides to co-operate with the respective spools of a group of spools of said series, rock shafts connected to the respective 110
 70 traverse rods, separate means for actuating the rock shafts of each of the traverse rods including a replaceable cam and gear, a traverse motion shaft having gears to co-operate with the respective cam gears and adjustable idle pinions for transmitting rotation from said traverse motion shaft to said cam gears.

8. A spooler comprising a frame having a series of aligned sections, a plurality of rotatable spool carriers mounted upon each section, means for rotating all the spools of all sections simultaneously and at a uniform speed, a traverse rod for each section having guides to co-operate with the respective spools of such section, a traverse motion shaft extending through all sections, separate traverse mechanisms mounted upon each section to actuate the traverse rod of such section and means for actuating each 115
 85 traverse mechanism from said traverse motion shaft.

9. A spooler comprising a frame having a series of rotatable spool carriers and means for imparting uniform rotation to all of 120
 95 said spool carriers, a plurality of traverse rods each having guides co-operating with the respective spools of a group of spools of said series, separate traverse mechanisms for actuating the respective traverse rods, a traverse motion shaft for actuating all of 100
 100 said traverse mechanisms, means for continuously driving said traverse motion shaft and means for preventing breakage of a 105
 105 traverse mechanism upon interruption of its proper operation.

10. A spooler comprising a frame having a series of rotatable spool carriers and means for imparting uniform rotation to all of 110
 110 said spool carriers, a plurality of traverse rods each having guides co-operating with the respective spools of a group of spools of said series, separate traverse mechanisms for actuating the respective traverse rods, comprising cams having attached gears and 115
 115 means for rotating said gears including a positively driven traverse motion shaft, gears rotatably mounted upon the traverse motion shaft and frictional clutch mechanisms normally securing the gears to the 120
 120 traverse motion shaft.

In testimony whereof, I have signed my name to this specification.

ALONZO E. RHOADES.
